UNITED STATES PATENT OFFICE

2,535,327

DRIER

Cornelius C. Smith, Slocomb, Ala.

Application August 10, 1949, Serial No. 109,527

7 Claims. (Cl. 34—164)

1

This invention relates to driers for peanuts, grain, and like material.

An object of the present invention is to provide a gravity flow type of drier in which vertically oscillated drying screens disposed within a casing are so arranged and controlled as to effectively spread the material and expose the maximum area of its surface to the drying action of air discharged into the casing, and in which the air is so discharged against the stream of material flowing from each screen to the next lower screen as to expedite the drying action and to allow a large volume of the material to flow rapidly through the drier.

Another object is to turn the screens on their pivots to set them at different selected maximum slopes, and mechanisms to oscillate the screens which include such means and are adjustable to vary the length of the arc through which the screens are oscillated, whereby to alter the speed of movement of the material through the casing in accordance with the requirements of said material.

A further object of the invention is to provide air discharge pipes which are adjustable laterally toward and from the streams of material flowing from screen to screen, and which are also rotatably adjustable about their axes to change the angle at which the air is discharged toward such streams of material, whereby a most efficient drying action may be had in accordance with the nature of the material.

Still another object is to provide means for mounting and oscillating the screens which are disposed outside the casing so as to be readily accessible and out of the path of the material being dried.

The nature of the present invention, as well as other objects and features thereof, will become apparent from the following description when considered in connection with the accompanying drawings, in which:

Figure 1 is a top plan view, partly broken away and in section, of the main portion of a drier constructed in accordance with the present invention;

Figure 2 is a vertical section taken on the line 2—2 of Figure 1;

Figure 3 is an enlarged fragmentary section taken on the line 3—3 of Figure 1;

Figure 4 is a vertical section taken on the line 4—4 of Figure 3;

Figure 5 is an enlarged fragmentary vertical section through the pivot shaft of one of the screens and adjacent parts.

Referring in detail to the drawings, 5 indicates

2

a vertically elongated casing of rectangular cross section, and 6 indicates screens which are disposed in vertically spaced relation and alternately mounted at opposite sides of the casing for vertical oscillation, each screen being pivotally mounted at one end on and outwardly of one side of the casing and projecting into the latter through a slot 7 therein to a point near but spaced from the opposite side of said casing. As shown, 10 each screen is fixed to a rock shaft 8 having its ends journaled in bearing brackets 9 attached to the casing. Attached to the casing and each screen, above and below the latter, are flexible strips 10 which are given sufficient fullness to permit oscillation of the screen, and which close the adjacent slot 7 to prevent escape of air from the casing through said slot.

In front of the casing and midway between the sides thereof is a vertical manifold 11 into which 20 air is suitably forced from a suitable source, and disposed across the casing from front to back thereof as well as below and beyond the free end of each screen is a perforated air discharge pipe 12 which is connected at one end to the manifold 11 by a flexible conduit 13 or the like. The ends of each pipe 12 extend through horizontally elongated slots 14 provided in the front and rear walls of the casing and through openings of slides 15 which cover slots 14 and are slidably mounted and frictionally fitted in guides 16 attached to the outside of the casing above and below said slots. Clamping bands 17 attached to the slides and embracing the ends of pipe 12 prevent escape of air from the casing through slots 14 and the openings of slides 15 about said pipe. The clamping bands 17 also hold the pipe 12 in any position to which it is rotatably adjusted about its axis. A further clamping band 18 releasably secures an end of pipe 12 in an end of the associated conduit 13. Each pipe 12 has a single row of apertures 19 therein, and it will be seen that the angle at which the air is discharged from the discharge pipe 12 toward the stream of material flowing from the end of one screen to the next lower screen past said discharge pipe may be changed by rotatably adjusting said discharge pipe about its axis. Also, by moving the slides 15, the discharge pipe 12 may be adjusted laterally toward or from the stream of material to obtain maximum drying efficiency. Of course the air will also spread and pass upwardly through the screens to act upon the material on the latter as the material is agitated and spread on said screen by oscillation of the latter in a vertical arc.

As the drying action depends to a great extent

on the speed of travel of the material being dried, it is desirable to vary such speed to suit the requirements of the material. To do this, I provide mechanisms for oscillating the screens which include means to set the screens at different maximum slopes and to vary the length of the arc through which the screens are oscillated. A screen oscillating mechanism is provided for the screens mounted at each side of the casing, and as both mechanisms are substantially alike, description of one will suffice. Each such mechanism includes a driven shaft 20 journaled in bearings 21 carried by bracket 22 fixed to a side of the casing near the bottom of the latter, a crank 23 secured on one end of said shaft, a relatively long lever 24 fixed to the pivot shaft 8 of the lowermost screen, a pitman 25 connecting the crank 23 with the other end portion of lever 24, a relatively short lever 26 fixed to the pivot shaft 8 of each screen, and a link connection 27 between the levers of adjacent screens. The connections between the links and the levers and between the pitman and the long lever are adjustable toward or from the pivot shafts of the screens for varying the length of the arcs through which the screens are oscillated, and the pitman and the links are adjustable in length to allow for said adjustment and to turn the screens on their pivots to set them at different selected maximum slopes. As shown, the levers have longitudinal slots 28 in which pivots of the pitman and links are adjusted, and the links are adjustable in length and consists of sections connected by turnbuckles 29. The pitman is also adjustable in length and consists of sections adjustably connected as at 30. Thus, the screens may be set and oscillated through arcs of different lengths as stated above. The screens are counter-balanced by means of springs 31 disposed on stems 32 pivoted to and depending from the levers 24 and extending loosely through guides 33 carried by brackets 23, the springs bearing at their ends against the guides 33 and abutments 34 adjustable on the stems 32 below said guides. By adjusting the abutments 34, the stems 32 may move in accordance with adjustments of the pitman and links when setting the screens for varying the length of their arc of oscillation. Each shaft 20 may have a pulley 35 secured on the other end thereof to facilitate transmission of power thereto from any suitable source.

The material to be dried may be fed into the casing through the top thereof and to the uppermost screen by any suitable means, and any suitable means may be provided at the bottom of the casing to collect or receive and discharge the dried material.

In operation, the mechanisms are driven to oscillate the screens, and the material supplied through the top of the casing will be spread on and will pass in succession over the screens, flowing in a sheet-like stream over the free end of each screen onto the next screen and from the lower screen to the bottom of the casing. Air supplied to the pipes 12 will be discharged from the latter toward and through the streams of material, in addition to passing upwardly through the screens and the material moving thereover, thereby thoroughly and rapidly drying the material by the time it flows from the lowermost screen.

From the foregoing description, it is believed that the construction, operation and advantages of the present invention will be readily under-

stood and appreciated by those skilled in the art. Modifications and changes in details of construction shown and described, are contemplated, such as fairly fall within the spirit and scope of the invention as claimed.

Having described the invention, what is claimed as new is:

1. A drier comprising a vertical casing, means to discharge air into the casing, a plurality of vertically spaced screens in the casing disposed in transversely staggered relation and adapted to successively discharge material onto each other from the uppermost one down, pivot mounting means for the screens at their opposite ends in alternating order, and mechanisms at opposite sides of the casing connected to the pivoted ends of the screens to oscillate the latter about their pivots through a vertical arc, said mechanisms including adjusting means to turn the screens on their pivots and set them at different maximum slopes.

2. A drier comprising a vertical casing having slots in opposite sides thereof, means to discharge air into the casing, a plurality of vertically spaced screens projecting into the casing through said slots, said screens being disposed in transversely staggered relation and adapted to successively discharge material onto each other from the uppermost one down, pivot mounting means for the screens outside the casing and at opposite ends of the screens in alternating order, flexible strips attached to the casing and to the screens above and below the latter for closing said slots, and mechanisms outside and at opposite sides of the casing to oscillate the screens about their pivots through a vertical arc.

3. A drier comprising a casing, a plurality of vertically spaced screens in the casing disposed in transversely staggered relation and adapted to successively discharge material onto each other from the uppermost one down, pivot mounting means for the screens at their opposite ends in alternating order, an air discharge pipe disposed across the casing parallel with the pivotal axis and below and beyond the free end of each screen so that the material will pass the same when passing from one screen to another, said pipes having perforations arranged to discharge the air toward the passing material, means to adjust said pipes laterally toward and from the passing material, means to rotatably adjust said pipes to vary the angle at which the air is discharged toward the passing material, and mechanisms at opposite sides of the casing to oscillate the screens about their pivots through a vertical arc.

4. A drier comprising a vertical casing having slots in opposite sides thereof, means to discharge air into the casing, a plurality of vertically spaced screens projecting into the casing through said slots, said screens being disposed in transversely staggered relation and adapted to successively discharge material onto each other from the uppermost one down, pivot mounting means for the screens outside the casing and at opposite ends of the screens in alternating order, means for closing said slots and permitting oscillation of the screens, and mechanisms at opposite sides of the casing to oscillate the screens about their pivots through a vertical arc.

5. The construction defined in claim 1, in combination with spring means associated with each mechanism for counterbalancing the screens operatively connected therewith.

6. A drier comprising a casing, a plurality of vertically spaced screens in the casing disposed in transversely staggered relation and adapted to successively discharge material onto each other from the uppermost one down, pivot mounting means for the screens at their opposite ends in alternating order, an air discharge pipe disposed across the casing parallel with the pivotal axis of and below and beyond the free end of each screen so that the material will pass the same in passing from one screen to another, said pipes having perforations arranged to discharge the air toward the passing material, means to adjust said pipes laterally toward and from the passing material, and mechanisms at opposite sides of the casing to oscillate the screens about their pivots through a vertical arc.

7. A drier comprising a casing, a plurality of vertically spaced screens in the casing disposed in transversely staggered relation and adapted to successively discharge material onto each other from the uppermost one down, pivot mounting means for the screens at their opposite ends in alternating order, an air discharge pipe disposed across the casing parallel with the

pivotal axis of and below and beyond the free end of each screen so that the material will pass the same in passing from one screen to another, said pipes having perforations arranged to discharge the air toward the passing material, means to rotatably adjust the pipes to vary the angle at which the air is discharged toward the passing material, and mechanisms at opposite sides of the casing to oscillate the screens about their pivots through a vertical arc.
